UNITED STATES PATENT OFFICE

DONALD S. BARROWS, OF ROCHESTER, NEW YORK, ASSIGNOR TO THE GOULD COUPLER COMPANY, OF NEW YORK, N. Y., A CORPORATION OF MARYLAND

RAILWAY TRUCK

Application filed October 10, 1927. Serial No. 225,238.

This invention relates to railway car trucks and more particularly to the construction of the side frames thereof and the supporting of the bolster thereby.

The principal object of my invention, generally considered, is to provide trucks particularly adapted for railway cars in which the side frames thereof are rigidified by an integral bridge which extends between intermediate portions of the bolster guide columns or struts leaving a space above the same for the bolster and below the same for the spring plank, said bridge portion serving to limit downward movement of the bolster and prevent the springs from going solid, means being provided for locking the bolster in place with respect to the associated side frames comprising a spring cap provided with upstanding outer guide portions which interlock with the bolster.

An object of my invention is to provide a car truck in which the side frames thereof are stiffened by integral bridges extending between intermediate portions of the bolster guide columns leaving bolster openings thereabove and spring plank openings therebelow said bridges being formed as laterally spaced portions receiving bolsters springs therebetween as well as outwardly and inwardly thereof, the tension member of the side frame being laterally widened for supporting such bolster springs. The inner and outer of said springs supporting a spring a spring cap which is apertured over the intermediate springs whereby it may be dropped upon removing said outer and inner springs, said spring cap being provided with upstanding lugs engaging the bolster guide columns or struts to provide removable outer guides, an associated bolster being correspondingly notched to interlock with said guides and being supported on said spring cap and springs.

Another object of my invention is to provide means for locking a bolster in assembled relation wth respect to an associated side frame, which frame is provided with a bolster opening insufficient in depth to permit dropping the bolster for the withdrawal thereof, said locking means comprising a

spring cap which overlies the outer and inner of the bolster springs and is apertured to receive the intermediate of said bolster springs whereby said spring cap may be dropped to release the bolster upon removal of the outer and inner springs only.

A further object of my invention is to provide a car truck with side frames stiffened by an integral bridge portion extending between intermediate portions of the bolster guide columns leaving a space thereabove for the bolster and a space therebeneath for the associated spring plank, a spring plank received on the tension member of said frame beneath the bridge portion and springs supported on said spring plank, certain of said springs extending between laterally spaced portions of the bridge member and the other springs being spaced on opposite sides of said bridge member, a spring cap supported on the outer and inner springs and apertured over the intermediate springs, said spring cap being provided with upstanding lugs adapted to form removable outer guides for the associated bolster and a bolster associated therewith and interlocking with said outer guide portions, the height of said guide portions being such that the bolster is disengageable therefrom upon removal of the outer and inner springs and dropping the spring cap over the intermediate springs to the bridge member and raising said bolster.

Other objects and advantages of the invention relating to the particular arrangement and construction of the various parts will become apparent as the description proceeds.

Referring to the drawings illustrating my invention, the scope whereof is defined by the appended claims,

Figure 1 is a partial side elevation of a truck illustrating an embodiment of my invention, a portion of the spring cap being illustrated in vertical section;

Fig. 2 is a partial transverse sectional view on the line 2—2 of Fig. 1 looking in the direction of the arrows; and

Fig. 3 is a partial horizontal sectional view on the line 3—3 of Fig. 1 looking in the direction of the arrows.

Referring to the drawings in detail, like parts being designated by like reference characters, there is shown a side frame 1 with a compression member 2, a tension member 3, and bolster guide columns or struts 4 spacing intermediate portions of said compression and tension members and leaving a bolster opening 5 therebetween. The intermediate portions of said bolster guide columns 4 are joined by an integral bridge member 6 which is spaced from the compression member a sufficient distance for receiving the associated bolster 7 and from the tension member a sufficient distance for receiving the associated spring plank 8. Said bridge 10 greatly rigidifies the frame and at the same time decreases the size of the bolster opening 5 so that the associated bolster 7 cannot be dropped for withdrawal in accordance with usual practice. Said bolster is therefore formed without the usual integral outer guides but is preferably provided with the usual inner guides 9.

The upper web 10 of the tension member 25 3 is widened between the bolster guide columns 4 to provide the required spring seating area therefor. The bolster springs 11 are supported on either side of the bridge member 6 and said bridge member is preferably formed as laterally spaced portions whereby the intermediate bolster springs are received therebetween.

The spring plank extends through the opening 12 between the bridge member 6 35 on the spring seating portion 10 of the tension member 3 and all the bolster springs 11 are supported thereon. Supported in turn on said bolster springs is a spring cap 13 provided with upstanding lugs 14 engaging the bolster guide columns 4 to provide outer lugs and wearing portions for the associated bolster 7. Said bolster 7 for that purpose is notched as indicated at 15 to receive the corresponding portions of the lugs 14 whereby 40 said lugs interlock with the bolster and provide outer guides for the same.

In order to facilitate removal and insertion of the bolster the spring cap 13 is preferably apertured over the intermediate 50 springs 16 and the bolster 7 is formed with a corresponding boss 17 interlocking in said aperture whereby said spring cap and its associated guide lugs are disengageable from the bolster upon removal of the inner and outer springs only, said cap being dropped over the intermediate springs on account of the aperture therein. The height of the lugs 13 is such that the bolster clears said lugs 55 when the spring cap is resting on the bridge 6 and the bolster is raised to the compression member 2.

From the foregoing disclosure it will be apparent that I have devised a railway truck construction in which the side frames thereof are strengthened by an integral bridge mem-

ber between intermediate portions of the guide columns and so spaced from the compression and tension members that provision is made for receiving both the bolster and spring plank in normal positions. Said bolster is provided with the usual integral inner guides and removable outer guides are provided therefor by using a spring cap with upstanding lugs interlocking with the bolster and engaging the outer portions of the bolster guide columns. Said spring cap is adapted to be dropped upon removal of the inner and outer springs only by being apertured over the intermediate springs which springs are preferably received between transversely spaced portions of the bridge and therefore less easily removed.

The lugs on the spring cap are preferably not as high as the depth of the bolster whereby disengagement between the bolster and spring cap may be effected upon removing the inner and outer springs by dropping the spring cap on the bridge and raising the bolster to the compression member.

In the present embodiment I have shown the bolster springs as comprising two spring units disposed outwardly and inwardly of the bridge and another pair of spring units disposed between the spaced portions of the bridge but it is obvious that I do not wish to be limited to this specific disclosure.

Having now described my invention, I claim,—

1. In a car truck, in combination, a side frame formed with a compression member, a tension member, struts interposed therebetween and spaced to leave a bolster opening, that portion of the tension member beneath the bolster opening being laterally widened for supporting bolster springs, a bridge member connecting said struts and formed as two laterally spaced portions permitting the reception of a plurality of longitudinally disposed springs therebetween, bolster springs supported on said portions of the bridge member between and on either side of said laterally spaced portions of the bridge member, a spring cap supported on the outer and inner springs of said bolster springs, a bolster formed with inner guides and notched outwardly of said guides, and upstanding lugs on said spring cap received in said notches and forming removable outer guides for said bolster.

2. In a car truck, in combination, a side frame formed with a compression member, a tension member, struts interposed therebetween and spaced to leave a bolster opening, that portion of the tension member beneath the bolster opening being laterally widened for supporting bolster springs, a bridge member connecting said struts and comprising a pair of portions so spaced that a plurality of longitudinally disposed bolster springs may be received therebetween, bol-

- ster springs supported on said laterally widened portions of the tension member between and on either side of said bridge portions, a spring cap supported on the outer 5 and inner springs of said bolster springs and apertured over the intermediate springs between those portions of the bridge member whereby said spring cap may be dropped upon removal of the inner and outer springs, 10 and a bolster formed with inner guides and provided with notches outwardly of said guides, said spring cap being provided with upstanding lugs receivable in said notches to provide removable outer guides for said 15 bolster.
3. In a car truck, in combination, a side frame formed with a compression member, a tension member, struts interposed therebetween and spaced to leave a bolster opening, that portion of the tension member beneath the bolster opening being laterally widened for supporting bolster springs, a bridge member connecting intermediate portions of said struts and spaced from the 20 laterally widened portion of the tension member to permit the insertion of a spring plank therebeneath, a spring plank supported on said laterally widened portions of the tension member beneath said bridge member, bolster springs supported on said spring plank adjacent said bridge member, a spring cap supported on said bolster springs and provided with upstanding portions serving as removable outer bolster guides, and a bolster supported on said spring cap and interlocking with the outer bolster guide portions thereof.
4. In a car truck, in combination, a side frame formed with a compression member, 40 a tension member, struts interposed therebetween and spaced to leave a bolster opening, that portion of the tension member beneath the bolster opening being formed for supporting bolster springs, a bridge member connecting said struts, bolster springs supported on said portions of the tension member between the struts, a spring cap supported on the outer and inner of said bolster springs, a bolster formed with inner guides 45 and notched outwardly of said guides and upstanding lugs on said spring cap received in said notches and providing removable outer guides for said bolster.
5. In a car truck, in combination, a side frame formed with a compression member, 55 a tension member, struts interposed therebetween and spaced to leave a bolster opening, the upper web of the tension member beneath the bolster opening being laterally widened for supporting bolster springs, a pair of spaced bridge members connecting said struts, a spring plank resting on the upper web of said tension member between said struts, bolster springs supported on said spring plank of said tension member between
- said struts and positioned outwardly, inwardly and intermediate said bridge members, a spring cap supported on the outer and inner of said bolster springs and formed with an aperture over the intermediate bolster springs, a bolster associated with said side frame and formed with inner guides and notches outwardly of said guides, said bolster being provided with a depending lug extending into the aperture in the spring cap and interlocking the same with respect thereto, said spring cap being provided with upstanding lugs forming outer guides for said bolster. 70
6. In a car truck, in combination, a side frame formed with a compression member, a tension member, struts interposed therebetween and spaced to leave a bolster opening, that portion of the tension member beneath the bolster opening being formed for supporting bolster springs, a tie member connecting intermediate portions of said struts, bolster springs supported on said tension member adjacent said tie, a spring cap supported on the outer and inner springs of said bolster springs, and a bolster formed without integral outer guides and provided instead with notches, said spring cap being formed with integral upstanding lugs interlocking in said notches to provide removable outer 80 guides for said bolsters. 85
7. In a car truck, in combination, a side frame formed with a compression member, a tension member, struts interposed therebetween and spaced to leave a bolster opening, the upper web of the tension member beneath the bolster opening being widened for properly supporting bolster springs, a pair of laterally spaced tie members connecting intermediate portions of said struts, a spring plank supported on said laterally widened upper web of the tension member beneath said tie members, bolster springs supported on said spring plank outwardly of, inwardly of and intermediate the tie members, a spring cap supported on the outer and inner springs only of said bolster springs and apertured over the intermediate springs whereby it may be dropped upon removal of said outer and inner springs, and a bolster formed with integral inner guides adapted to engage the inner portions of said struts and notched and spaced from said struts outwardly thereof, 90 said spring cap being provided with upstanding angular lugs receivable in said notches, filling the space between said bolster and lugs and providing outer bolster guides. 100
8. In a car truck, in combination, a side frame formed with a compression member, a tension member, bolster guide columns interposed therebetween and spaced to leave a window opening, that portion of the upper web of the tension member beneath the window member being widened beyond the side webs thereof for supporting bolster springs, 110 120 125 130

- a tie member connecting intermediate portions of said bolster guide columns and dividing the window opening into two parts for respectively receiving the associated bolster and spring plank, a spring plank supported on said upper web of the tension member beneath the tie member, bolster springs supported on said spring plank adjacent said tie member, a spring cap supported on said bolster springs and provided with upstanding portions providing removable outer bolster guides, and a bolster supported on said spring cap and interlocking with said bolster guides.
9. A spring cap for bolster springs comprising a normally horizontal portion adapted for support by inner and outer springs and apertured for passing over intermediate springs whereby said cap may be dropped upon removal of said outer and inner springs only.
10. A spring cap for bolster springs comprising a normally horizontal plate portion adapted for support by the outer and inner springs only of said bolster springs and apertured over the intermediate springs thereof whereby it is adapted to receive a corresponding lug on the associated bolster, said cap being provided with upstanding lugs adapted to interlock in corresponding notches in an associated bolster, and providing removable outer guides therefor.

In testimony whereof I affix my signature.
DONALD S. BARROWS.
